UNITED STATES PATENT OFFICE.

JAMES M. LEWIS, OF DOWNERS GROVE, ILLINOIS, ASSIGNOR TO BRU-SHOE-MATIC COMPANY, OF CHICAGO, ILLINOIS, A CORPORATION OF ILLINOIS.

DESIGN FOR A CASING FOR A SHOE-BRUSHING MACHINE.

Application filed November 5, 1928. Serial No. 28,768. Term of patent 3½ years.

To all whom it may concern:

Be it known that I, JAMES M. LEWIS, a citizen of the United States, residing at Downers Grove, in the county of Du Page and State of Illinois, have invented a new, original, and ornamental Design for Casing for a Shoe-Brushing Machine, of which the following is a specification, reference being had to the accompanying drawing, forming part thereof.

The figure is a perspective view of a casing for a shoe brushing machine, showing my new design.

I claim:

The ornamental design for a casing for a shoe brushing machine, as shown.

JAMES M. LEWIS.
